(57) **CLAIM**

The ornamental design for a device for storing and carrying vehicle battery jumper cables, as shown and described.

DESCRIPTION

FIG. 1 is a perspective view of a device for storing and carrying vehicle battery jumper cables.

FIG. 2 is a front elevational view thereof.

FIG. 3 is a rear elevational view thereof.

FIG. 4 is a top view thereof.

FIG. 5 is a bottom view thereof.

FIG. 6 is a right side elevational view thereof; and,

FIG. 7 is a left side elevational view thereof.

The broken lines depict environment that forms no part of the claimed design.

1 Claim, 5 Drawing Sheets
